UPHOLSTERY FABRIC

Edward A. Smith, Haworth, N. J.

Application September 5, 1957, Serial No. 47,612

Term of patent 14 years

(Cl. D92—1)

The figure is a plan view of an upholstery fabric, showing my new design. A unit of the design is indicated in broken lines in the drawing. Such unit is repeated in regular succession throughout the fabric.

I claim:

The ornamental design for an upholstery fabric, as shown and described.
